TYPEWRITING MACHINE

John Joseph Kittel, St. Albans, N. Y., assignor
to Royal Typewriter Company, Inc., New York,
N. Y., a corporation of New York

Application December 21, 1940, Serial No. 371,196

31 Claims. (Cl. 197—66)

This invention relates to typewriting machines, and, more particularly, to mechanism for returning the carriages of such machines after the typing of a line to position the carriage in readiness for the starting of another line of typing.

In most conventional or standard typewriters, the carriages are returned manually, usually through the instrumentality of a combined line-spacing and carriage-returning lever or handle. Various kinds of power-operated mechanism have been provided for returning the carriages in order to eliminate manual effort and increase speed of operation. Most of such mechanisms previously provided have had some objectionable characteristics, such as jerky operation resulting from the quick pick-up of the drive returning the carriage, which is hard on the entire machine and conducive to undesirably noisy operation.

An object of the present invention is to provide an improved carriage return mechanism in which these objections are overcome. In accordance with the invention, an impositive or cushioned drive is interposed between a motive member and the carriage so that the picking up of the carriage load is cushioned and jerking of the carriage is eliminated, but, at the same time, no undesirable delay in returning the carriage to its starting position is encountered.

Another object is to provide carriage return mechanism including an impositive fluid drive coupling.

A further and important object of the invention is to provide, in connection with carriage-returning mechanism of the character stated, a brake controllable at the will of the operator for regulating the speed of the returning carriage.

Another object is to provide an improved brake and brake-actuating mechanism.

Another object is to provide carriage return drive and carriage return braking mechanism of the character referred to under the conjoint control of manually operable means of such character that the operator can effect return of the carriage and can control the return travel speed in a simple and convenient manner.

Another object is to provide mechanism having the desirable drive-cushioning characteristics previously referred to and which is adapted to drive the carriage in both the letter-spacing and return directions.

Another object is to provide cushioned carriage return driving mechanism arranged to effect

line-spacing movement of the typewriter platen prior to the return movement of the carriage.

A further object is to provide mechanism of the character referred to so constructed and arranged as to be capable of being applied easily as an attachment to standard typewriters.

Other objects will become apparent from a reading of the following detailed description, the appended claims, and the accompanying drawings, in which:

Figure 1 is a fragmentary side elevation of a typewriter equipped with mechanism embodying the invention in one form, some of the standard or known typewriter parts being omitted;

15 Figure 2 is a longitudinal vertical section of fluid-coupled driving means, the section being taken on the line 2—2 of Figure 4;

Figure 3 is a fragmentary view in rear elevation showing mechanism embodying the invention applied to a typewriter, some of the known and conventional typewriter parts being omitted;

20 Figure 4 is a fragmentary top plan view of a typewriter equipped with mechanism embodying the invention, some of the known or standard typewriter parts being omitted;

Figure 5 is a vertical section taken on the line 5—5 of Figure 1;

Figure 6 is a detailed section taken on the line 6—6 of Figure 1;

30 Figure 7 is a longitudinal view, partly in section and partly in elevation, showing an impositive drive coupling and reversing gearing embodied in a modification shown further in Figures 8 and 9;

35 Figure 8 is a fragmentary rear view of the modified embodiment, some parts being shown in elevation and others in section on the line 8—8 of Figure 9; and

Figure 9 is a section on the line 9—9 of Figure

40 8, with most parts appearing in elevation.

Embodiment shown in Figures 1 to 6, inclusive

One form of mechanism embodying the invention is shown in Figures 1 to 6, inclusive, as being applied to a Royal standard typewriter including a frame generally designated A and a carriage generally designated B mounted for letter-spacing and return movements on the frame through the instrumentality of ball rollers 45. The carriage B is equipped with the usual platen C rotatable for line-spacing purposes.

Mechanism for imparting rotary line-spacing movements to the platen C includes a line-spacing lever 2 pivoted on the carriage as at 3. One end 50 of a link 4 is pivotally connected at 5 to the

line-spacing lever 2, and the other end of the link is pivotally connected as at 6 to a rock arm 7 which carries a pawl 8 cooperable with a ratchet wheel 9 secured to the platen, the arrangement being such that rocking of the line-spacing lever 2 toward the rear of the typewriter will project the link 4 rearwardly to rock the arm 7 and move the pawl 8 into engagement with the ratchet wheel 9 to rotate the platen C a predetermined amount for line-spacing. A spring 10 interposed between a hook 11 on the line-spacing lever 2 and a stud 12 on the carriage B normally maintains the line-spacing lever in its inactive position as shown in Figure 4.

The carriage may be driven in the letter-spacing direction in the usual manner by means of a spring barrel 13 having wound thereon a draw band 14, the free end of which is connected as at 14^a to the carriage. Movement of the carriage in the letter-spacing direction under the urge of the spring barrel 13 and draw band 14 is controlled in the usual manner by escapement mechanism of a known kind, and only parts of which are shown. Referring to Figure 4, the escapement mechanism includes an escapement wheel 15 cooperable with the usual dogs one, 16, of which is shown. The escapement wheel is connected by a pawl 15^a to an escapement pinion 17 which meshes with an escapement rack 18 mounted on the carriage B. Movement of the carriage in the letter-spacing direction is limited by engagement of a margin stop 19 mounted on a margin stop bar 20 with a center stop 20^a. Movement of the carriage in the return direction is limited by engagement of a margin stop 21 with the center stop 20^a. The parts described thus far are of known construction and organization. The present invention relates more particularly to other parts to be described, the combinations of such other parts with each other, and the combinations of such other parts with the known parts already described.

Carriage return mechanism constructed in accordance with the present invention may be applied to a typewriter either in the building of the typewriter or as an attachment to an existing typewriter. In the form shown, the mechanism is adapted for attachment to an existing typewriter, and includes a mounting plate 22 secured to the typewriter frame A by means of four posts 23. An electric motor 24 is secured by means of screws 25 to a bracket 26 which in turn is secured to the mounting plate 22 by screws 27. The motor 24 is arranged to transmit drive through an impositive drive coupling generally designated D to a carriage return driving mechanism generally designated E.

The impositive drive coupling shown is of the kinetic fluid medium type similar to that disclosed in my copending application Serial No. 327,707, filed April 3, 1940. The coupling includes a large diameter pulley 28 formed with a hub 29 journaled in a bearing 30 fixed in an extension 31 of the mounting plate 22. The pulley 28, which constitutes the motive element of the coupling, that is, the element which introduces motive power to the coupling, is driven from the electric motor 24 by means of a belt 32 looped around a motor pulley 33 and an idler pulley 34 journaled as at 35 on a clevis bracket 36 secured to the mounting plate 22 by screws 37. The small pulleys 33 and 34 are disposed below the large pulley 28, and the upper stretch of the belt loop peripherally engages the pulley 28 at its bottom. As a result of this arrangement, the small pulleys 33

34 and 34 and belt 32 are disposed at a low level, thereby minimizing the danger of paper or clothing becoming caught between the belt and any of the pulleys with which it engages.

5 The reduced end of a shaft 38 is mounted to rotate freely in a bore 39 formed in the hub 28. Adjacent its opposite end the shaft 38 is mounted to rotate in a bearing 40 fast in a bushing 41 fixedly mounted in a bracket 42 secured by 10 screws 43 to the mounting plate 22. A fluid coupling impeller section 44 is mounted to turn freely on the shaft 38 and is secured by screws 44^a to the web of the pulley 28. The impeller 44 and a bulge 45 in the pulley web together form 15 the housing of the fluid coupling device. The hub 46 of the impeller is elongated and is provided at its outer end with a bellows seal 47 adjustable by a nut 48 for maintaining the interior of the housing sealed against the escape of working fluid indicated at F.

Vanes 49 fixed to the impeller 44 are cooperable through the medium of the fluid F with vanes 50 carried by a coupling runner 51 secured by a pin 52 to the shaft 38. The adjacent end of the shaft is formed with a longitudinal passage 53 and a lateral passage 54 for enabling the introduction of working fluid through an opening in the hub 28 normally closed by a screw plug 55.

Mounted on the opposite end of the shaft 38 is a carriage return driving member or winding drum 56 secured to the shaft by a screw 57 which serves also to connect to the drum a draw band 58 windable upon the drum. The draw band extends from the drum around a pulley 59 journaled on a bracket 60 secured by screws 61 to the usual tabulator finger cover 62, and thence around a pulley 63 journaled on a bracket 64 secured as at 65 to the carriage B. The band extends from the pulley 63 forwardly to the line-spacing mechanism, the end of the band being secured by a screw 66 to an arcuate segment 67 pivoted on the carriage as at 3 and pinned as at 68 to the line-spacing lever 2 to rock in unison therewith.

45 In operation, motor drive transmitted through the belt 32 to the pulley 28 and impeller 44 drives the runner 51 through the fluid F, thereby rotating the shaft 38 and winding drum 56 so as to pull on the band 58. The initial movement of the band will rock the segment 67, and, with it, the line-spacing lever 2, to effect line-spacing movement of the platen C. When the line-spacing operation has been completed, further pulling of the draw band 58 will move the carriage in the return direction, movement of the various parts at this stage of the operation being indicated by the arrows a in Figures 1, 2, 3, and 4. Preferably, the motor 24 normally is inactive and is started by means later to be described for initiating the line-spacing operation and return movement of the carriage. The motor, upon being started, will come up to speed quickly, but this will occasion no undesirable shocks because the impositive drive afforded by the fluid coupling acts as a cushion, causing the inertia of the stationary carriage to be overcome smoothly and gradually, although without undesirable delay. The capacity of the fluid F to transmit drive is nil when the impeller moves very slowly. The driving effect of the fluid F increases as its kinetic energy is increased by being rotated by the impeller 44 at progressively increasing speed. Consequently, the fluid coupling automatically provides the desired cushioning of the carriage drive and brings the carriage up to the desired

return travel speed quickly. It will be observed that the drive-transmitting connections between the motive pulley 28 and the carriage do not include any parts such as clutch elements which have to be brought into engagement after the motive pulley has been started. Instead, the drive connections between the pulley 28 and the carriage are always conditioned for the transmission of carriage return driving effort.

During return-travel drive of the carriage transmitted by the fluid coupling, energy-storing movement will be imparted to the spring barrel 13 in preparation for subsequent letter-spacing carriage drive. When the carriage reaches the end of its return travel and is arrested by engagement of the margin stop 21 with the center stop 20a, it will be held positively against further movement and without rebound. The carriage may be arrested in this way without its being necessary to stop the motor immediately, because the slip of fluid in the impositive drive fluid coupling D will permit the impeller 44 to continue to rotate while the runner 51 remains stationary.

In accordance with a feature of the invention, means is provided for retarding the carriage during its return movement prior to the engagement of the margin stop 21 with the center stop 20a in order to prevent the margin stop 21 from striking the center stop 20a with too much force. To this end, a brake is located on the carriage side of the coupling D, the arrangement being such that the brake retards the winding drum 56 without, however, retarding the motive pulley 28 and impeller 44. The brake includes a drum 69 formed integrally with the winding drum 56, and being thereby constrained to rotate with the shaft 38. A polished steel brake band 70 partially surrounds the drum 69 and has its free ends equipped with springs 71 connected to means under the control of the operator for resiliently urging the band 70 into frictional engagement with the drum 69.

Preferably, the brake and carriage return driving means are operable conjointly. A combined carriage return drive-effecting and carriage retarding key 72 fulcrumed on the frame A as at 73 is pivotally connected as at 74 to the front end of a push bar or link 75. The rear end of the link 75 is pivotally connected as at 76 to one arm 77 of a lever 78 having a pintle 79 journaled in a bushing 80 fixed to the mounting plate 22. The other arm 81 of the lever 78 is formed with a hooked end 82 to which the springs 71-71 are connected. By depressing the key 72, the link 75 will be thrust rearwardly, and the lever 78 will be rocked in a counterclockwise direction as viewed in Figure 1, thereby pulling down on the springs 71 and resiliently urging the band 70 into engagement with the brake drum 69.

Mounted on the push link 75 is a switch-operating cam generally designated 83 formed with an inclined cam surface 84 cooperable with a spring arm 85 for moving the arm up against and depressing a button 86 on a switch 87 in circuit with the motor 24. The switch may be secured to the bracket 26 by screws 88. Initial depressing movement of the key 72, and consequent rearward movement of the link 75, will bring the cam surface 84 into engagement with the spring arm 85 to push the button 86 and close the motor circuit. During continued depressing movement of the key and rearward movement of the link 75, the spring arm 85 will be maintained in operative engagement with the switch button 86

by an extended dwell 89 on the cam 83. The arrangement is such that during initial movement of the key the cam surface 84 will close the switch; and during progressively further movements of the key the switch will be maintained closed by the dwell 89, and the brake band 70 will be applied to the brake drum 69 with progressively increasing force.

Because of the impositive action of the drive coupling D, the carriage may be moved manually in either direction without restraint by the carriage driving mechanism by actuating the usual escapement releasing mechanism (not shown). In order that manual movement of the carriage in the return direction will not produce looseness in the draw band 58, a helical spring 90 is secured by a screw 91 to the brake drum 69, and is secured by a screw 92 to the bushing 41, which provides a fixed anchorage for the adjacent end of the spring 90. The spring is so tensioned that it normally tends to rotate the brake drum 69 and winding drum 56 to maintain the draw band 58 taut at all times.

Embodiment shown in Figures 7 to 9, inclusive

Figures 7, 8, and 9 show an embodiment in which the carriage is driven in both directions by mechanism including an impositive drive coupling. The known or conventional typewriter parts, such as the frame A, the carriage B, and the escapement rack 18 are designated by the same reference characters as designate the corresponding parts in the embodiment shown in Figures 1 to 6, inclusive. A plate 93 which is secured to the frame A by means of posts 94 and screws 95 serves to mount a carriage-driving and carriage return speed control mechanism including reversing gearing generally designated G, an impositive drive coupling H, a carriage-driving drum or pulley element I, and a looped band J arranged to be driven by the pulley I for moving the carriage B in both the letter-spacing and the return direction, depending upon the direction of rotation of the pulley I.

The looped band J may be trained or supported to extend in the direction of carriage travel in any suitable manner, for example, in a manner similar to the mounting of the carriage driving band in the copending application Serial No. 327,707 previously referred to. As shown in Figure 8, the band J extends partially around and in contact with the carriage-driving pulley I, and one stretch of the band extending from the pulley passes in contact with a guide pulley 96 journaled on a bracket 97 supported on the frame A. From the pulley 96, the band extends around a tensioning pulley 98 journaled on an arm 99 pivoted as at 100 on the bracket 97, and being urged to tension the band by means of a spring 101 connected to an adjusting screw 102. A stretch J of the band extends from the pulley 98 along in back of the carriage and is connected to a bracket 103 on the carriage. Thence the band extends around guide pulleys 104 and 105 journaled on a bracket 106 supported on the main frame, and around a guide pulley 107 journaled on a bracket 108 supported on the main frame A. The band passes around and in contact with a drum 109 journaled as at 110 on the main frame A and bracket 108, around a guide pulley 111 carried by the bracket 108, and a guide pulley 112 journaled on the bracket 81, thence returning to the driving pulley I and completing the loop. The drum 109 may be provided with a gear, a portion of which is indicated at 113 in mesh with

a pinion 114 mounted on a ribbon feed drive shaft 115 adapted to be connected by suitable means (not shown) to ribbon spool operating mechanism.

The mechanism mounting plate 93 is provided with an ear 116 and a bracket 117 which respectively support bushings 118 and 119. The pulley I, which provides one-half of the housing of the fluid coupling H, includes a web 120 and a hub 121 which is journaled for rotation in the bushing 118. The other half of the coupling housing comprises a housing section 122 secured to the first-named housing section by means of screws 123. The pulley hub 121 is formed with a bore 124 in which is mounted for rotation the reduced end of a shaft 125 which passes freely through the hub 126 of the housing section 122, and is journaled in a bearing 127 supported in the bushing 119. An opening in the pulley web 120 normally closed by a plug 120a provides for the introduction of fluid F into the coupling housing.

The runner housing section 122 is provided with internal radial vanes 128 which are cooperable, through the medium of the fluid F, with radial vanes 129 on a coupling impeller 130 pinned at 131 to the shaft 125. In operation, the shaft 125 is rotated by means later to be described, and, through the medium of the fluid F which is whirled by the vanes 129, drives the coupling housing or runner impositively so as to provide the driving force necessary to move the carriage B in the letter-spacing or the return direction, depending upon the direction of rotation of the shaft 125.

The coupling runner section 122 is formed integrally with a brake drum 132 adapted to cooperate in a manner to be described with a polished steel brake band 133. A bellows seal 134, which bears against the brake drum and is adjustable by means of a nut 135, maintains the coupling housing sealed against leakage of operating fluid F along the shaft 125. The shaft projects to the left (as viewed in Figure 7) beyond the seal 134, and mounts two driven bevel gears 136 and 137 which are constrained against axial movement along the shaft, but which rotate freely with respect to the shaft. Both of the driven gears 136 and 137 are in constant mesh with a motive bevel gear 138 adapted to be driven in the direction of the arrow b in Figure 7 by a motor indicated generally at 139. The bevel gear 136 is provided with a hub 140 which abuts against the adjacent end of the bearing 127 to prevent movement of the gear 136 toward the right. Movement of the gear 136 to the left is prevented by its engagement with the driving or motive gear 138. The driven bevel gear 137 is provided with a hub 141 which is in end-to-end relation with a ball thrust bearing 142 abutting against a bracket 143 supported on the mounting plate 93, the gear 137 thereby being held against axial movement to the left. Meshing of the gear 137 with the gear 138 prevents axial movement of the gear 137 toward the right.

The gears 136 and 137 are driven in opposite directions as indicated respectively by the arrows c and d in Figure 7, and are adapted selectively to be coupled or clutched to the shaft 125 so as to drive the impeller 130 in the desired direction. To this end, the gear 136 is provided with a toothed surface 144 which is opposed to and faces, but is spaced from, a toothed surface 145 on the gear 137. A shiftable clutch device or sleeve 146 is splined to the shaft 125 as at 147, and is provided at its opposite ends with teeth

148 and 149 respectively adapted to be engaged with the toothed surfaces 144 and 145. The sleeve 146 is formed with a groove 150 adapted to receive rollers one, 151, of which is shown as being mounted on a fork lever 152 pivoted on the mounting plate 93 as at 153. A spring 154 interposed between a stud 155 on the mounting plate 93 and an arm 156 projecting from the fork lever 152 normally urges the sleeve 146 to the right so as to maintain the teeth 148 of the sleeve in mesh with the toothed surface 144 of the gear 136. Accordingly, the shaft 125 normally will be driven in the direction of the arrow e in Figure 8 so as to drive the band J in the direction of the arrow f and urge the carriage in the letter-spacing direction. When the sleeve 146 is shifted toward the left from the position shown in Figures 7 and 9, it first will pass through a neutral position, in which it has operative connection with neither of the gears 136 and 137, and then will become operatively connected to the gear 137 through the medium of the sleeve teeth 149 and the toothed surface 145 on the gear 137. The shaft 125 and coupling impeller 130 then will be driven in the direction opposite the arrow e so as to drive the pulley I and band J also in the opposite direction, and move the carriage in the return direction.

Control means is provided for shifting the sleeve 146 to effect the reversal as set forth above, and also for applying the brake band 133 to the brake drum 132, the arrangement being such that the brake band is caused to retard the drum 132 and shaft 125 while the sleeve 146 is passing through its neutral position so as to reduce the relative speed of the sleeve and the gear 137 with which it is to be connected or clutched, thus facilitating meshing of the sleeve teeth 149 with the toothed surface 145 on the gear 137. The control means shown includes a key lever 157 pivotally mounted as at 158 on the frame A. A link 159 is pivotally connected at its front end as at 160 to the key lever 157, and is pivotally connected at its rear end as at 161 to an arm 162 of a compound lever 163 pivoted on the mounting plate 93 as at 164. Another arm 165 of the lever 163 is connected to both ends of the brake band 133 by means of springs 166 which enable the brake band to be applied to the drum 132 yieldingly or resiliently. Another arm 167 of the compound lever 163 is pivoted as at 168 to a link 169, the rear end of which is pivoted as at 170 to a cam plate 171 which is pivoted as at 172 on the mounting plate 93. A spring 173 interposed between the stud 155 and an arm 174 projecting downwardly from the cam plate 171 normally urges the cam against a stop lug 175 carried by the plate 93. The cam is formed with a low portion 176, an inclined cam rise 177, and an extended or long dwell portion 178. A resilient spring arm 179 fast with the fork lever 152 carries a cam follower roller 180 engaging the cam plate 171.

In operation, the motor 139 normally will drive the beveled gears 136 and 137 in the directions indicated respectively by the arrows c and d in Figure 7, and the spring 154 will maintain the fork lever 152 and clutch sleeve 146 in the positions shown in Figures 7 and 9, so that the bevel gear 136 will be clutched to the shaft 125. Consequently, the shaft 125 and fluid coupling impeller 130 will be driven in the direction indicated by the arrow e in Figure 8, tending to rotate the carriage-driving pulley I in the same

direction, and thus tending to move the carriage in the letter-spacing direction as indicated by the arrow *f* in Figure 8. When the escapement mechanism has not been operated to release the carriage for letter-spacing movement, the carriage will be held at rest, as is permitted by the impositive action of the kinetic type fluid coupling. When the escapement mechanism is operated to permit letter-spacing, the fluid coupling will provide the necessary operative connection between the shaft 125 and the carriage B for moving the carriage a letter space. During this time, the brake band 133 is not effectively applied to the drum 132.

When it is desired to return the carriage preparatory to the typing of a new line, the key lever 157 is depressed, thus thrusting the link 159 rearwardly, rocking the compound lever 163 in a counterclockwise direction as viewed in Figure 9, thrusting the link 169 rearwardly, and rocking the cam 171 in a counterclockwise direction against the urge of the spring 173. The rise 177 of the cam will elevate the roller 180, thus rocking the resilient arm 179 and the fork lever 152 in a counterclockwise direction so as to disengage the sleeve 146 from the gear 136. Simultaneously, the brake band 133 is applied to the brake drum, and, while the sleeve 146 is passing through its neutral position, during which it has no operative connection with either of the gears 136 and 137, the brake band 133 will act effectively on the drum 132 to retard the shaft 125 so as to reduce the relative rotative speeds of the sleeve 146 and the gear 137, and thereby facilitate smooth engagement of the sleeve with the gear 137, and lessen the strain incident to reversal of the direction of rotation of the shaft 125 and the parts rotatable with it. After the sleeve 146 has been operatively engaged with the gear 137, the shaft 125 and coupling impeller 130 will rotate in the reverse direction, and, through the medium of the fluid F, will drive the coupling runner and pulley I so as to drive the carriage B in the return direction. The speed of movement of the carriage during its return travel may be controlled by further depression of the key lever 157, which will apply the brake band 133 resiliently through the springs 166 with progressively increased force against the brake drum 132. After the cam follower roller 180 has passed over the rise 177 and onto the long dwell 178, the cam 171 may continue to rock in response to further depression of the key 157 without any operative effect upon the fork lever 152, thus permitting the key 157 to be depressed progressively after reversal of the drive so as to produce progressively increasing braking effect.

The mechanisms shown herein embody the invention in the now preferred forms, but various changes may be made without departing from the invention as defined in the claims.

I claim:

1. In carriage driving mechanism for a typewriting or the like machine including a frame and a carriage mounted thereon for letter-spacing and return travel, a motive element; a carriage-return driving member; means providing driving connection between said member and said carriage; means including an impositive drive transmitting kinetic type fluid coupling interposed between said motive element and said driving member and being constantly conditioned to transmit drive from said motive element to said driving member; and means for starting and stopping said motive element.

2. In carriage driving mechanism for a typewriting or the like machine including a frame and a carriage mounted thereon for letter-spacing and return travel, an electric motor; a carriage-return driving member; means providing driving connection between said member and said carriage; means including an impositive drive transmitting kinetic type fluid coupling interposed between said motor and said driving member and being constantly conditioned to transmit drive from said motor to said driving member; and a switch in circuit with said motor for starting and stopping said motor.

3. In carriage driving mechanism for a typewriting or the like machine including a frame and a carriage mounted thereon for letter-spacing and return travel, a motive element; a rotatable carriage-return driving member; connections including a kinetic type fluid coupling interposed between said motive element and said driving member, said coupling including a rotatable impeller operatively connected to said motive element, a rotatable runner operatively connected to said driving member, and drive-transmitting fluid operatively associated with said impeller and said runner, all of said connections between the driving member and the motive element being constantly conditioned for transmitting impositive drive from said motive element to said driving member; and means for starting and stopping said motive element.

4. In carriage driving mechanism for a typewriting or the like machine including a frame and a carriage mounted thereon for letter-spacing and return travel, a motive element; a rotatable carriage-return driving member; connections including a kinetic type fluid coupling interposed between said motive element and said driving member, said coupling including a rotatable impeller operatively connected to said motive element, a rotatable runner operatively connected to said driving member, and drive-transmitting fluid operatively associated with said impeller and said runner, all of said connections between the driving member and the motive element being constantly conditioned for transmitting impositive drive from said motive element to said driving member, said fluid coupling constituting a necessary part of the only operable train of driving connections between said motive element and said carriage; and means for starting and stopping said motive element.

5. In carriage driving mechanism for a typewriting or the like machine including a frame and a carriage mounted thereon for letter-spacing and return travel, a motive element; a rotatable winding drum; a draw band wound on said drum and being connected to said carriage; connections including a fluid coupling interposed between said motive element and said winding drum, said coupling including a rotatable impeller operatively connected to said motive element, a rotatable runner operatively connected to said drum, and drive-transmitting fluid operatively associated with said impeller and said runner; means for starting and stopping said motive element, said connections between said motive element and said winding drum being constantly conditioned for transmitting impositive drive from said motive element to said winding drum; and a spring having a fixed anchorage and also being connected to said drum for constantly urging the drum to wind up the draw band, whereby to maintain said draw band taut.

6. In carriage driving mechanism for a type-

writing or the like machine including a frame and a carriage mounted thereon for letter-spacing and return travel, a motor; and driving connections between the motor and the carriage comprising a pulley drivingly connected to said carriage, a motor pulley connected to said motor to be driven thereby, an idler pulley, and a belt trained over said motor pulley and said idler pulley to form a continuous loop, the outside of one stretch of the loop engaging the pulley which is connected to the carriage.

7. In carriage driving mechanism for a type-writing or the like machine including a frame and a carriage mounted thereon for letter-spacing and return travel, a motor mounted low on said frame; and driving connections between the motor and carriage comprising a large diameter pulley journaled on the frame above the motor and being drivingly connected to the carriage, a small diameter idler pulley journaled on the frame below the large diameter pulley, a small diameter motor pulley connected to said motor to be driven thereby, and a belt trained over said small diameter pulleys, the belt being disposed below said large diameter pulley and the outside of the upper stretch of the belt engaging a part of the periphery of the large diameter pulley at the bottom thereof.

8. In carriage driving mechanism for a type-writing or the like machine including a frame and a carriage mounted thereon for letter-spacing and return travel, a motive element; a carriage-return driving member; means providing driving connection between said member and said carriage; impositive drive means interposed between said motive element and said driving member and being constantly conditioned to transmit drive from said motive element to said driving member; a brake on the carriage side of said impositive drive means for retarding carriage-return movement without stopping said motive element; and means operable at will for applying said brake.

9. In carriage driving mechanism for a type-writing or the like machine including a frame and a carriage mounted thereon for letter-spacing and return travel, a motive element; a carriage-return driving member; means providing driving connection between said member and said carriage; impositive drive means interposed between said motive element and said driving member and being constantly conditioned to transmit drive from said motive element to said driving member; a brake on the carriage side of said impositive drive means for retarding carriage-return movement without stopping said motive element; and control means for starting said motive element and applying said brake.

10. In carriage driving mechanism for a type-writing or the like machine including a frame and a carriage mounted thereon for letter-spacing and return travel, a motive element; a carriage-return driving member; means providing driving connection between said member and said carriage; means including an impositive drive-transmitting fluid coupling interposed between said motive element and said driving member and being constantly conditioned to transmit drive from said motive element to said driving member; a brake on the carriage side of said fluid coupling for retarding carriage-return movement; and means operable at will for applying said brake.

11. In carriage driving mechanism for a type-writing or the like machine including a frame and a carriage mounted thereon for letter-spacing

and return travel, a motive element; a carriage-return driving member; means providing driving connection between said member and said carriage; means including an impositive drive-transmitting fluid coupling interposed between said motive element and said driving member and being constantly conditioned to transmit drive from said motive element to said driving member; a brake on the carriage side of said fluid coupling for retarding carriage-return movement; and control means for starting said motive element and applying said brake.

12. In carriage driving mechanism for a type-writing or the like machine including a frame and a carriage mounted thereon for letter-spacing and return travel, a motive element; a carriage-return driving member; means providing driving connection between said member and said carriage; means including an impositive drive-transmitting fluid coupling interposed between said motive element and said driving member and being constantly conditioned to transmit drive from said motive element to said driving member; a normally ineffective brake on the carriage side of said fluid coupling adapted when rendered effective to retard carriage-return movement; a device for starting said motive element; a combined carriage-return movement-effecting and carriage-return movement retarding key; and connections between said key, said starting device, and said brake for operating said starting device upon initial movement of the key and for applying said brake upon further movement of said key.

13. In carriage driving mechanism for a type-writing or the like machine including a frame and a carriage mounted thereon for letter-spacing and return travel, a motor; carriage-return driving connections including an impositive drive coupling between the motor and carriage; means for starting the drive from said motor to said carriage; a brake drum operatively connected to the carriage on the carriage side of said impositive drive coupling and being rotatable in response to carriage-return travel; a normally ineffective brake band associated with said drum; a key; and connections between said key, said brake band, and said drive starting means for starting the drive upon initial movement of the key and for maintaining said drive and applying said brake band to said drum with progressively increasing force upon progressive further movement of the key.

14. In carriage driving mechanism for a type-writing or the like machine including a frame and a carriage mounted thereon for letter-spacing and return travel, a motor; carriage return driving connections including an impositive drive coupling between the motor and carriage; means for starting the drive from said motor to said carriage; a brake drum operatively connected to the carriage on the carriage side of said impositive drive coupling and being rotatable in response to carriage return travel; a normally ineffective brake band associated with said drum; a key; and connections between said key, said brake band, and said drive starting means including yieldable means between the key and the brake band for starting the drive upon initial movement of the key and for maintaining said drive and applying said brake band to said drum with progressively increasing force upon progressive further movement of the key.

15. In carriage driving mechanism for a type-writing or the like machine including a frame

and a carriage mounted thereon for letter-spacing and return travel, an electric motor; carriage return driving connections including an impositive drive coupling between the motor and carriage; a switch in circuit with said motor; a brake member operatively connected to the carriage on the carriage side of said impositive drive coupling and being movable in response to carriage return movement; a cooperable brake member; a key; a switch-operating cam movable in response to actuation of said key for closing said switch; and means connecting said key to said cooperable brake member.

16. In carriage driving mechanism for a typewriting or the like machine including a frame and a carriage mounted thereon for letter-spacing and return travel, an electric motor; carriage return driving connections between the motor and carriage; a switch in circuit with said motor; a brake member movable in response to carriage return movement; a cooperable brake member; a key; a switch-operating cam movable in response to actuation of said key for closing said switch; and means connecting said key to said cooperable brake member, said switch-operating cam having an extended dwell for maintaining said switch closed throughout different amounts of movement of the key effecting different braking effort of said cooperable brake member on said first-named brake member.

17. In carriage driving mechanism for a typewriting or the like machine including a frame and a carriage mounted thereon for letter-spacing and return travel, an electric motor; carriage return driving connections between the motor and carriage; a switch in circuit with said motor; a brake member movable in response to carriage return movement; a cooperable brake member; a key; a push rod connected to said key; a cam carried by said push rod and being engageable with said switch for closing the latter upon initial movement of the key and push rod, said cam having a dwell to maintain the switch closed during further movement of the key and push rod; and resilient means connecting said push rod to said cooperable brake member.

18. In carriage driving mechanism for a typewriting or the like machine including a frame and a carriage mounted thereon for letter-spacing and return travel, a motor; carriage return driving connections between the motor and carriage; means for starting the drive from said motor to said carriage; a brake drum rotatable in response to carriage return travel; a normally ineffective brake band associated with said drum; a key; a link connected to said key; means movable by said link for actuating the drive-starting means in response to initial movement of said key; a lever connected to said link; and springs interposed between said lever and the respective ends of said brake band for resiliently applying said band to said drum with progressively increasing force in response to progressively further movements of said key.

19. In a typewriting or the like machine, a frame; a carriage mounted thereon for letter-spacing and return travel; a platen rotatable on said carriage for line-spacing; line-spacing mechanism on said carriage associated with said platen; a motive element; a rotatable winding drum; a draw band wound on said drum and being operatively connected to said line-spacing mechanism; connections including a fluid coupling interposed between said motive element,

and said winding drum, said coupling including a rotatable impeller operatively connected to said motive element, a rotatable runner operatively connected to said drum, and drive-transmitting fluid operatively associated with said impeller and said runner, said connections between said motive element and said winding drum being constantly conditioned for transmitting impositive drive from said motive element to said winding drum; and means for starting and stopping said motive element, winding up of the draw band on the drum first operating said line-spacing mechanism and then moving the carriage in return direction, termination of the line-spacing operation and starting of carriage return travel being cushioned by said fluid coupling.

20. In carriage driving mechanism for a typewriting or like machine including a frame and a carriage mounted thereon for letter-spacing and return travel, a carriage drive pulley journaled on said frame; a looped carriage driving band peripherally engaging said carriage drive pulley; guide pulleys journaled on said frame and training a stretch of the band to extend in the direction of carriage movement and adjacent the carriage; means connecting said stretch of the band to said carriage; a motive element; and carriage letter-spacing and return travel driving connections between said motive element and said carriage drive pulley including an impositive drive coupling and reversing gearing interposed between said coupling and said motive element.

21. In carriage driving mechanism for a typewriting or like machine including a frame and a carriage mounted thereon for letter-spacing and return travel, a carriage drive pulley journaled on said frame; a looped carriage driving band peripherally engaging said carriage drive pulley; guide pulleys journaled on said frame and training a stretch of the band to extend in the direction of carriage movement and adjacent the carriage; means connecting said stretch of the band to said carriage; a motive element; and carriage letter-spacing and return travel driving connections between said motive element and said carriage drive pulley including a kinetic type fluid coupling and reversing gearing interposed between said coupling and said motive element.

22. In carriage driving mechanism for a typewriting or like machine including a frame and a carriage mounted thereon for letter-spacing and return travel, a carriage driving member; a motor driven element; driving connections between said member and said element including shiftable reversing gearing and an impositive drive coupling, the coupling being operatively arranged between the reversing gearing and the carriage driving member; a brake operable on said connections between said coupling and said gearing; and control means for first applying said brake and then shifting said reversing gearing to effect carriage-return drive.

23. In carriage driving mechanism for a typewriting or like machine including a frame and a carriage mounted thereon for letter-spacing and return travel, a carriage driving member; a motor driven element; driving connections between said member and said element including reversing gearing and an impositive drive coupling, said reversing gearing including two oppositely rotatable gears driven by said motor-driven element and a device shiftable for selec-

tive engagement with said gears and being adapted to be disengaged from both gears temporarily during shifting movement, said coupling being operatively connected between said shiftable device and said carriage driving member; a brake operable on said connections on the carriage side of said shiftable device; and control means for shifting said device to effect carriage-return drive and for applying said brake during shifting and when said device is disengaged from both of said gears.

24. In carriage driving mechanism for a typewriting or like machine including a frame and a carriage mounted thereon for letter-spacing and return travel, a carriage driving member; a motor driven element; driving connections between said member and said element including reversing gearing and a kinetic type fluid coupling, said reversing gearing including two oppositely rotatable gears driven by said motor-driven element and a device shiftable for selective engagement with said gears and being adapted to be disengaged from both gears temporarily during shifting movement, said coupling being operatively connected between said shiftable device and said carriage driving member; a brake operable on said connections on the carriage side of said shiftable device; and control means for shifting said device to effect carriage-return drive and for applying said brake during shifting and when said device is disengaged from both of said gears.

25. In carriage driving mechanism for a typewriting or like machine including a frame and a carriage mounted thereon for letter-spacing and return travel, a carriage driving member; a motor-driven element; driving connections between said member and said element including reversing gearing and a kinetic type fluid coupling, said reversing gearing including two oppositely rotatable gears driven by said motor-driven element and a device shiftable for selective engagement with said gears and being adapted to be disengaged from both gears temporarily during shifting movement, said coupling being operatively connected between said shiftable device and said carriage driving member; a brake drum rotatable with said connections between the reversing gearing and said coupling; a brake band; a lever connected to said shiftable device for shifting the latter; an operating member; and connections between said lever, said brake band, and said operating member for shifting said device to effect carriage return drive and for applying said brake while said device is being shifted and is disengaged from both of said gears.

26. In carriage driving mechanism for a typewriting or like machine including a frame and a carriage mounted thereon for letter-spacing and return travel, a carriage driving member; a motor driven element; driving connections between said member and said element including a shaft, two coaxial gear rotatable about said shaft in opposite directions by said motor-driven element, toothed clutch parts on said gears respectively, a toothed clutch element shiftable on said shaft between said clutch parts for selective engagement therewith and being splined to said shaft to rotate therewith, and a fluid drive coupling interposed between said shaft and said carriage driving member; a brake drum rotatable with said shaft; a cooperable brake band; a lever for shifting said clutch element; key-operated control mechanism; a resilient connection between said control mechanism and said brake band; and a

resilient connection between said control mechanism and said lever.

27. In carriage driving mechanism for a typewriting or like machine including a frame and a carriage mounted thereon for letter-spacing and return travel, a carriage drive pulley journaled on said frame; a looped carriage driving band peripherally engaging said carriage drive pulley; guide pulleys journaled on said frame and training a stretch of the band to extend in the direction of carriage movement and adjacent the carriage; means connecting said stretch of the band to said carriage; a motive bevel gear; a shaft at right angles to the axis of rotation of said gear; 10 two bevel gears freely rotatable on said shaft and being in mesh with said motive gear to be driven in opposite directions thereby; spaced opposed toothed surfaces on said gears respectively; a clutch sleeve splined to and shiftable on said shaft between said driven gear toothed surfaces and having its opposite ends provided with teeth adapted to engage selectively with the respectively adjacent driven gear toothed surfaces; a lever for shifting said sleeve on said shaft to 15 effect such selective engagement; a spring urging said lever to effect engagement of the sleeve with that one of said driven gears which, when thus connected to the shaft, will effect letter-spacing carriage movement; means impositively coupling said shaft to said carriage drive pulley; a brake drum rotatable with said shaft; a cooperable brake element; a key; means operable by said key for effecting cooperation of said cooperable brake element with said brake drum; a cam; a cooperable cam follower; a resilient connection between said cam follower and said shifting lever; and means operable by the key for moving said cam to effect shifting of said lever and engagement of the sleeve with the other of said driven gears to thereby effect carriage return drive.

28. In carriage driving mechanism for a typewriting or the like machine including a frame and a carriage mounted thereon for letter-spacing and return travel, a motive element; carriage-return driving connections between the motive element and the carriage; means for starting the drive from said motive element to said carriage to effect return travel thereof; a brake for retarding the carriage during its return travel; a manually operable control member; and connections between said control member, said drive-starting means, and said brake for operating said drive-starting means and applying said brake in response to manual operation of said control member, said connections including a cam movable in response to operation of said control member and having an inclined portion and a long dwell, and a cam follower connected to said drive-starting means and being movable by said cam inclined portion for starting the drive, said follower being adapted to contact said cam dwell idly during progressive further operation of said control member with consequent application of progressively increasing braking effort.

29. In a typewriting or the like machine, a frame; a carriage mounted thereon for letter-spacing and return travel; a platen rotatable on said carriage for line-spacing; line-spacing mechanism on said carriage associated with said platen; a spring barrel mounted on said frame; 70 a first draw band secured to and wound upon said barrel and being connected to said carriage, movement of the carriage in the return direction winding the spring associated with the barrel and storing energy therein, said stored

and a carriage mounted thereon for letter-spacing and return travel, an electric motor; carriage return driving connections including an impositive drive coupling between the motor and carriage; a switch in circuit with said motor; a brake member operatively connected to the carriage on the carriage side of said impositive drive coupling and being movable in response to carriage return movement; a cooperable brake member; a key; a switch-operating cam movable in response to actuation of said key for closing said switch; and means connecting said key to said cooperable brake member.

16. In carriage driving mechanism for a typewriting or the like machine including a frame and a carriage mounted thereon for letter-spacing and return travel, an electric motor; carriage return driving connections between the motor and carriage; a switch in circuit with said motor; a brake member movable in response to carriage return movement; a cooperable brake member; a key; a switch-operating cam movable in response to actuation of said key for closing said switch; and means connecting said key to said cooperable brake member, said switch-operating cam having an extended dwell for maintaining said switch closed throughout different amounts of movement of the key effecting different braking effort of said cooperable brake member on said first-named brake member.

17. In carriage driving mechanism for a typewriting or the like machine including a frame and a carriage mounted thereon for letter-spacing and return travel, an electric motor; carriage return driving connections between the motor and carriage; a switch in circuit with said motor; a brake member movable in response to carriage return movement; a cooperable brake member; a key; a push rod connected to said key; a cam carried by said push rod and being engageable with said switch for closing the latter upon initial movement of the key and push rod, said cam having a dwell to maintain the switch closed during further movement of the key and push rod; and resilient means connecting said push rod to said cooperable brake member.

18. In carriage driving mechanism for a typewriting or the like machine including a frame and a carriage mounted thereon for letter-spacing and return travel, a motor; carriage return driving connections between the motor and carriage; means for starting the drive from said motor to said carriage; a brake drum rotatable in response to carriage return travel; a normally ineffective brake band associated with said drum; a key; a link connected to said key; means movable by said link for actuating the drive-starting means in response to initial movement of said key; a lever connected to said link; and springs interposed between said lever and the respective ends of said brake band for resiliently applying said band to said drum with progressively increasing force in response to progressively further movements of said key.

19. In a typewriting or the like machine, a frame; a carriage mounted thereon for letter-spacing and return travel; a platen rotatable on said carriage for line-spacing; line-spacing mechanism on said carriage associated with said platen; a motive element; a rotatable winding drum; a draw band wound on said drum and being operatively connected to said line-spacing mechanism; connections including a fluid coupling interposed between said motive element

and said winding drum, said coupling including a rotatable impeller operatively connected to said motive element, a rotatable runner operatively connected to said drum, and drive-transmitting fluid operatively associated with said impeller and said runner, said connections between said motive element and said winding drum being constantly conditioned for transmitting impositive drive from said motive element to said winding drum; and means for starting and stopping said motive element, winding up of the draw band on the drum first operating said line-spacing mechanism and then moving the carriage in return direction, termination of the line-spacing operation and starting of carriage return travel being cushioned by said fluid coupling.

20. In carriage driving mechanism for a typewriting or like machine including a frame and a carriage mounted thereon for letter-spacing and return travel, a carriage drive pulley journaled on said frame; a looped carriage driving band peripherally engaging said carriage drive pulley; guide pulleys journaled on said frame and training a stretch of the band to extend in the direction of carriage movement and adjacent the carriage; means connecting said stretch of the band to said carriage; a motive element; and carriage letter-spacing and return travel driving connections between said motive element and said carriage drive pulley including an impositive drive coupling and reversing gearing interposed between said coupling and said motive element.

21. In carriage driving mechanism for a typewriting or like machine including a frame and a carriage mounted thereon for letter-spacing and return travel, a carriage drive pulley journaled on said frame; a looped carriage driving band peripherally engaging said carriage drive pulley; guide pulleys journaled on said frame and training a stretch of the band to extend in the direction of carriage movement and adjacent the carriage; means connecting said stretch of the band to said carriage; a motive element; and carriage letter-spacing and return travel driving connections between said motive element and said carriage drive pulley including a kinetic type fluid coupling and reversing gearing interposed between said coupling and said motive element.

22. In carriage driving mechanism for a typewriting or like machine including a frame and a carriage mounted thereon for letter-spacing and return travel, a carriage driving member; a motor driven element; driving connections between said member and said element including shiftable reversing gearing and an impositive drive coupling, the coupling being operatively arranged between the reversing gearing and the carriage driving member; a brake operable on said connections between said coupling and said gearing; and control means for first applying said brake and then shifting said reversing gearing to effect carriage-return drive.

23. In carriage driving mechanism for a typewriting or like machine including a frame and a carriage mounted thereon for letter-spacing and return travel, a carriage driving member; a motor driven element; driving connections between said member and said element including reversing gearing and an impositive drive coupling, said reversing gearing including two oppositely rotatable gears driven by said motor-driven element and a device shiftable for selec-

tive engagement with said gears and being adapted to be disengaged from both gears temporarily during shifting movement, said coupling being operatively connected between said shiftable device and said carriage driving member; a brake operable on said connections on the carriage side of said shiftable device; and control means for shifting said device to effect carriage-return drive and for applying said brake during shifting and when said device is disengaged from both of said gears.

24. In carriage driving mechanism for a typewriting or like machine including a frame and a carriage mounted thereon for letter-spacing and return travel, a carriage driving member; a motor driven element; driving connections between said member and said element including reversing gearing and a kinetic type fluid coupling, said reversing gearing including two oppositely rotatable gears driven by said motor-driven element and a device shiftable for selective engagement with said gears and being adapted to be disengaged from both gears temporarily during shifting movement, said coupling being operatively connected between said shiftable device and said carriage driving member; a brake operable on said connections on the carriage side of said shiftable device; and control means for shifting said device to effect carriage-return drive and for applying said brake during shifting and when said device is disengaged from both of said gears.

25. In carriage driving mechanism for a typewriting or like machine including a frame and a carriage mounted thereon for letter-spacing and return travel, a carriage driving member; a motor-driven element; driving connections between said member and said element including reversing gearing and a kinetic type fluid coupling, said reversing gearing including two oppositely rotatable gears driven by said motor-driven element and a device shiftable for selective engagement with said gears and being adapted to be disengaged from both gears temporarily during shifting movement, said coupling being operatively connected between said shiftable device and said carriage driving member; a brake drum rotatable with said connections between the reversing gearing and said coupling; a brake band; a lever connected to said shiftable device for shifting the latter; an operating member; and connections between said lever, said brake band, and said operating member for shifting said device to effect carriage return drive and for applying said brake while said device is being shifted and is disengaged from both of said gears.

26. In carriage driving mechanism for a typewriting or like machine including a frame and a carriage mounted thereon for letter-spacing and return travel, a carriage driving member; a motor driven element; driving connections between said member and said element including a shaft, two coaxial gear rotatable about said shaft in opposite directions by said motor-driven element, toothed clutch parts on said gears respectively, a toothed clutch element shiftable on said shaft between said clutch parts for selective engagement therewith and being splined to said shaft to rotate therewith, and a fluid drive coupling interposed between said shaft and said carriage driving member; a brake drum rotatable with said shaft; a cooperable brake band; a lever for shifting said clutch element; key-operated control mechanism; a resilient connection between said control mechanism and said brake band; and a

resilient connection between said control mechanism and said lever.

27. In carriage driving mechanism for a typewriting or like machine including a frame and a carriage mounted thereon for letter-spacing and return travel, a carriage drive pulley journaled on said frame; a looped carriage driving band peripherally engaging said carriage drive pulley; guide pulleys journaled on said frame and training a stretch of the band to extend in the direction of carriage movement and adjacent the carriage; means connecting said stretch of the band to said carriage; a motive bevel gear; a shaft at right angles to the axis of rotation of said gear; two bevel gears freely rotatable on said shaft and being in mesh with said motive gear to be driven in opposite directions thereby; spaced opposed toothed surfaces on said gears respectively; a clutch sleeve splined to and shiftable on said shaft between said driven gear toothed surfaces and having its opposite ends provided with teeth adapted to engage selectively with the respectively adjacent driven gear toothed surfaces; a lever for shifting said sleeve on said shaft to effect such selective engagement; a spring urging said lever to effect engagement of the sleeve with that one of said driven gears which, when thus connected to the shaft, will effect letter-spacing carriage movement; means impositively coupling said shaft to said carriage drive pulley; a brake drum rotatable with said shaft; a cooperable brake element; a key; means operable by said key for effecting cooperation of said cooperable brake element with said brake drum; a cam; a cooperable cam follower; a resilient connection between said cam follower and said shifting lever; and means operable by the key for moving said cam to effect shifting of said lever and engagement of the sleeve with the other of said driven gears to thereby effect carriage return drive.

28. In carriage driving machinism for a typewriting or the like machine including a frame and a carriage mounted thereon for letter-spacing and return travel, a motive element; carriage-return driving connections between the motive element and the carriage; means for starting the drive from said motive element to said carriage to effect return travel thereof; a brake for retarding the carriage during its return travel; a manually operable control member; and connections between said control member, said drive-starting means, and said brake for operating said drive-starting means and applying said brake in response to manual operation of said control member, said connections including a cam movable in response to operation of said control member and having an inclined portion and a long dwell, and a cam follower connected to said drive-starting means and being movable by said cam inclined portion for starting the drive, said follower being adapted to contact said cam dwell idly during progressive further operation of said control member with consequent application of progressively increasing braking effort.

29. In a typewriting or the like machine, a frame; a carriage mounted thereon for letter-spacing and return travel; a platen rotatable on said carriage for line-spacing; line-spacing mechanism on said carriage associated with said platen; a spring barrel mounted on said frame; a first draw band secured to and wound upon said barrel and being connected to said carriage, movement of the carriage in the return direction winding the spring associated with the barrel and storing energy therein, said stored

energy then serving to drive the carriage in the letter-spacing direction; a motive element; a rotatable winding drum; a second draw band wound on said drum and being operatively connected to said line-spacing mechanism; a fluid coupling interposed between said motive element and said winding drum, said coupling including a rotatable impeller operatively connected to said motive element, a rotatable runner operatively connected to said drum, and drive-transmitting fluid operatively associated with said impeller and said runner; and means for starting and stopping said motive element, winding up of the second draw band on the drum first operating said line-spacing mechanism and then moving the carriage in return direction and imparting energy storing winding action to said spring barrel, termination of the line-spacing operation and starting of carriage return travel being cushioned by said fluid coupling.

30. In a typewriting or the like machine, a frame; a carriage mounted thereon for letter-spacing and return travel; stop means for limiting the return travel of said carriage; a platen rotatable on said carriage for line-spacing; line-spacing mechanism on said carriage associated with said platen; a spring barrel mounted on said frame; a first draw band secured to and wound upon said barrel and being connected to said carriage, movement of the carriage in the return direction winding the spring associated with the barrel and storing energy therein, said stored energy then serving to drive the carriage in the letter-spacing direction; a motive element; a rotatable winding drum; a second draw band wound on said drum and being operatively connected to said line-spacing mechanism; a fluid coupling interposed between said motive element and said winding drum, said coupling including a rotatable impeller operatively connect- 40

ed to said motive element, a rotatable runner operatively connected to said drum, and drive-transmitting fluid operatively associated with said impeller and said runner; and means for starting and stopping said motive element, winding up of the second draw band on the drum first operating said line-spacing mechanism and then moving the carriage in return direction and imparting energy-storing winding action to said spring barrel, termination of the line-spacing operation and starting of carriage return travel being cushioned by said fluid coupling, said cushion drive fluid coupling preventing rebound of said carriage upon termination of the carriage return travel by said stop means.

31. In carriage driving mechanism for a typewriting or the like machine including a frame and a carriage mounted thereon for letter-spacing and return travel, a spring barrel mounted on said frame; a draw band secured to and wound upon said barrel and being connected to said carriage, movement of said carriage in the return direction winding the spring associated with said barrel and storing energy therein, said stored energy then serving to drive said carriage in the letter-spacing direction; a motive element; a carriage-return driving member; means providing driving connection between said member and said carriage; means including an im- 35 positive drive transmitting fluid coupling interposed between said motive element and said driving member and being constantly conditioned to transmit drive from said motive element to said driving member for moving the carriage in the return direction and imparting energy-storing winding action to said spring barrel; and means for starting and stopping said motive element.

JOHN JOSEPH KITTEL.
